JOHN F. METTEN, OF PHILADELPHIA, PENNSYLVANIA, ASSIGNOR TO THE WILLIAM CRAMP & SONS SHIP & ENGINE BUILDING COMPANY, A CORPORATION OF PENNSYLVANIA.

MARINE STEAM-TURBINE.

1,300,287.

Specification of Letters Patent. Patented Apr. 15, 1919.

Application filed September 9, 1915. Serial No. 49,661.

To all whom it may concern:

Be it known that I, JOHN F. METTEN, a citizen of the United States, residing at Philadelphia, in the county of Philadelphia 5 and State of Pennsylvania, have invented certain new and useful Improvements in Marine Steam-Turbines, of which the following is a full, clear, and exact specification.

This invention relates to marine steam turbines for driving a propeller shaft, and has for its object to increase the overall efficiency as compared with constructions previously used. The invention has particular reference to turbines composed of 10 several wheel or compound velocity stages followed by a solid headed drum carrying a number of single rows of either impulse or reaction blades. The best efficiency of this type of turbine depends upon reducing the wheel or compound velocity stages to the least possible number, and carrying as many blades as possible on the drum, because the drum is the more efficient part of 15 the turbine. In marine turbine installations, where the propeller is directly coupled to the turbine shaft, it has been customary to cause the pressure on the head of the drum to be about equal to or slightly in excess of the propeller thrust, in order to 20 save wear on the thrust blocks. In some instances, a part of this thrust has been produced by the reaction blading on the drum, but where impulse blading is used, the entire thrust opposing the propeller has been 25 exerted by the total steam pressure on the drum. As the diameter of the drum stages, whether of the reaction or of the impulse type, is determined by the blade speed, the steam volume, etc., it has been the common 30 practice to carry the expansion of the steam in the wheel stages before admitting it to the drum stages farther than is desired for the best overall economy, since the drum 35 stages are always of better efficiency than the wheel stages. One reason for doing this has been in order to secure the requisite low steam pressure on the head of the drum so as not to produce a backward thrust too 40 much in excess of the forward propeller 45 thrust.

According to the present invention, a marine steam turbine is provided in which the relatively inefficient wheel stages are re-

duced to a minimum, and in which the pressure at the beginning of the drum stage is 55 higher than has heretofore been employed, while at the same time enabling the backward thrust on the drum head to be maintained at or about equal to the forward propeller thrust. Thereby, a large number of 60 relatively inefficient wheel stages can be replaced by relatively efficient drum stages working at the same pressure, so that the overall efficiency of the plant is very much 65 increased.

In the specific embodiment of the invention herein shown, one of the forward wheels, preferably the initial one, is provided with a small drum, one side of said drum being subjected to steam pressure led from one of the lower stages, for example, from the first drum stage, and the other side of the drum being subjected to the steam pressure on the rear of the first wheel. The total rearward pressure exerted by the main 70 drum in opposition to the propeller thrust is thus reduced, so that the number of drum stages which can be employed is not limited by the necessity of coördinating the drum pressure to the propeller thrust. Further 75 advantages of this construction, other than that of increased overall economy, are that the forward gland of the turbine is not subjected to the initial high steam pressure in the first wheel stage, as is the usual practice, but is only subjected to the same rearward pressure as that applied to the auxiliary drum. The gland is thus simpler in 80 construction, and easier to keep in order. Also, the forward bearing is farther removed from the high temperature steam in 85 the first stage and will run cooler. The head of the turbine casing is also subjected to less total pressure, and consequently has less 90 tendency to deflection.

In the accompanying drawing, 1 represents a turbine casing in which a propeller shaft 2 is journaled in forward bearing 3, and a rearward bearing not shown, in the usual manner. 4 represents a propeller carried by shaft 2. 5 represents the forward gland, which is ordinarily subjected to the same pressure as that admitted to the first stage. Mounted on the shaft 2 are one or more high pressure wheels 6, and rearwardly 100 thereof is a drum 7 having forward head 8.

The wheels 6 have passages through them to equalize the pressure on the opposite faces of their webs and 9 are diaphragms carrying nozzles 10 of any desired construction, and separating the several wheel stages. The forward nozzles 10 are supplied with high pressure steam by a belt 11. The several wheel stages are provided with fixed and moving blades of any usual construction, but preferably the blades are of the impulse type. The drum 7 is also provided with fixed and moving blades, which may be either of the impulse or of the reaction type, or partly of both.

15 Mounted on the forward side of the first wheel 6 is a ring 13, which coöperates with a concentric ring 14 carried by the casing to form a steam tight joint. Ordinary gland packing rings may be used for this purpose. The chamber 16 thereby formed is connected by pipe 17 to a chamber 18 formed in the casing of the drum stages, and at such a point therein as will provide pressure sufficient to reduce the total rearward pressure on the main drum head 8 to the desired amount.

30 The rearward pressure produced by drum 8 tending to oppose the thrust of the propeller will be equal to the total effective area of the drum 8 multiplied by the steam pressure on the forward side thereof, which will considerably exceed the forward thrust of the propeller. At the same time, there will be a forward thrust on that portion of the first wheel 6 which is included within the ring 13, this thrust being produced by the steam pressure in the first wheel stage multiplied by the effective area of this auxiliary drum. By partially or wholly balancing this force by steam through the pipe 17, from one of the lower drum stages, it will be seen that the total pressure of drum 8 is reduced so as to balance the propeller thrust to the desired extent. The combination of the auxiliary forward drum with the main drum renders it possible to bring the latter forward into the higher pressure stages of the turbine to replace wheel stages, and also to increase the diameter of the drum, without necessitating too great a rearward drum thrust. The elimination of wheel stages effects a large saving in the cost of building a turbine, besides increasing the overall efficiency. As will be seen from the drawing, the auxiliary drum chamber communicates with the forward gland, and prevents the initial high pressure steam from acting thereon. This saves wear and special construction to resist high pressure, and also maintains the forward bearing at a lower running temperature.

65 It will be obvious that the auxiliary forward drum need not be carried by the initial forward wheel, but it is advantageous to put the drum on the forward wheel, rather

than on one of the intermediate wheels, owing to the reduction of the gland pressure, thereby effected, and also because it does not increase the overall length of the turbine, or require expensive reconstruction 70 of the casing. The pipe 17 can be connected at any point in the drum stages where the desired pressure is found, depending upon the particular installation.

Various modifications and changes may 75 be made in the construction herein illustrated without departing from the scope of the appended claims.

Having thus described my invention, what I declare as new and desire to secure 80 by Letters Patent of the United States is:—

1. In a steam turbine drive for a ship, the combination with a propeller shaft having a driving thrust in one direction of a series of steam turbine stages for driving said shaft and mounted on a drum having an axial thrust opposite to the driving thrust of said propeller shaft, a plurality of turbine wheel stages driving said shaft, said drum stages being substantially greater in 90 number than said wheel stages so as to increase the efficiency of the drive, and means for exerting a counter thrust to counterbalance the excess of said drum thrust and permit the relatively large number of drum 95 stages, comprising means for reducing the rearward pressure on one of said wheels.

2. In a steam turbine drive for a ship, the combination with a propeller shaft having a driving thrust in one direction of a series of steam turbine stages for driving said shaft and mounted on a drum having an axial thrust opposite to the driving thrust of said propeller shaft, a plurality of turbine wheel stages driving said shaft, said drum stages 100 being substantially greater in number than said wheel stages so as to increase the efficiency of the drive, and means for exerting a counter thrust to counterbalance the excess of said drum thrust and permit the relatively large number of drum stages comprising a dummy drum on one of said wheels having an annular steam tight packing engagement with the turbine casing and its 105 interior pressure reduced to increase the 110 pressure on its head in the direction of said propeller thrust.

3. In a steam turbine drive for a ship, the combination with a propeller shaft having a driving thrust in one direction of a series 120 of steam turbine stages for driving said shaft and mounted on a drum having an axial thrust opposite to the driving thrust of said propeller shaft, a plurality of turbine wheel stages driving said shaft, said 125 drum stages being substantially greater in number than said wheel stages so as to increase the efficiency of the drive, and means for exerting a counter thrust to counterbalance the excess of said drum thrust and 130

permit the relatively large number of drum stages comprising a web for one of said turbine wheels having a passage therethrough to equalize the pressure on each side 5 of said web and a dummy drum on one of said wheels having an annular steam tight packing engagement with the turbine casing and its interior pressure reduced to increase

the pressure on its head in the direction of said propeller thrust. 10

In testimony whereof I affix my signature in presence of two witnesses.

JOHN F. METTEN.
